By their Attorney,

Charles C. Gill.

UNITED STATES PATENT OFFICE.

ALFRED INGRAM AND HARRY INGRAM, OF BROOKLYN, NEW YORK, ASSIGNORS TO INGRAMS INCORPORATED, OF BROOKLYN, NEW YORK, A CORPORATION OF NEW YORK.

CLOSURE FOR JARS, BOTTLES, AND OTHER RECEPTACLES.

1,365,832.

Specification of Letters Patent.

Patented Jan. 18, 1921.

Application filed November 15, 1916, Serial No. 131,388. Renewed June 11, 1920. Serial No. 388,346.

To all whom it may concern:

Be it known that we, ALFRED INGRAM and HARRY INGRAM, citizens of the United States, and residents of Brooklyn, in the county of 5 Kings and State of New York, have invented certain new and useful Improvements in Closures for Jars, Bottles, and other Receptacles, of which the following is a specification.

10 The invention pertains more particularly to closures of cap character formed of flexible material, as celluloid, for example, having a depending flange or skirt portion to closely engage the side walls of a receptacle,

15 and the purpose of the invention is to insure the proper application of the closure to the receptacle. Considerable difficulty has heretofore been encountered in the use of flexible closures or caps of the class here involved by reason of the fact that on the application of the cap to the receptacle the air contained within the cap has become trapped and more or less compressed therein, with the result that the air has effected the lifting 25 of the cap from the receptacle.

Our invention provides a novel method of so applying the cap to the receptacle that the air which would otherwise become entrapped therein may escape, without the cap 30 itself being permanently vented. We find that it is very desirable to make the cap or closure of thin sheet pyroxylin material or the like, as celluloid, and to provide thereon a depending skirt portion which will very 35 closely engage the sides of the receptacle to which the cap or closure may be applied, and we have found that a cap or closure thus constructed necessarily, under usual conditions, entraps a considerable quantity of air 40 within it when applied to a receptacle, and to eliminate this objectionable condition and thereby insure the proper retention of the cap or closure on the receptacle, is the purpose of our invention, which we carry out by 45 extending a string or cord over the top of one side of the receptacle prior to or on applying the cap thereto, and after the cap has been applied, withdrawing said string or cord from between the cap and receptacle.

50 The presence of the string or cord between the cap and receptacle creates a temporary vent through which the air which would otherwise become entrapped may escape, and upon the final withdrawal of the string

or cord from between the cap and receptacle, 55 the said vent becomes closed by the natural tendency of the skirt of the cap or closure to resume its normal shape and engage the side of the receptacle, the result being that the cap or closure when once applied in the 60 manner described, remains in position and the receptacle continues to be properly closed and substantially air tight. The cap and string or cord may be independently applied, the string or cord being placed across 65 the upper edge of one side of the receptacle and allowed to extend down the outer side thereof and the cap then applied thereupon, or, as we prefer, the string or cord may be threaded through the skirt of the cap or 70 closure so as to be carried thereby and the string or cord and cap together applied to the receptacle, said string or cord, after the application of the cap or closure to the receptacle, being withdrawn so as to leave the 75 receptacle properly closed.

The invention will be fully understood from the detailed description hereinafter presented, reference being had to the accompanying drawings, in which:

Fig. 1 is a side elevation, partly in section, of a receptacle and cap shown as ready to be assembled for the closing of the receptacle, the cap being in vertical section and carrying the string or cord constituting one 85 of the features of our invention;

Fig. 2 is a vertical section through the cap and a portion of the receptacle, the cap being shown as having been applied to position and the string or cord as still upon the receptacle;

Fig. 3 is a side elevation, partly in section, of the receptacle and cap, the cap being in section and in its final condition and position, the string or cord having been 95 withdrawn;

Fig. 4 is a bottom view of the cap or closure embodying our invention;

Fig. 5 is an enlarged horizontal section through a portion of the receptacle and cap 100 on the dotted line 5 of Fig. 2;

Fig. 6 is a corresponding view on the dotted line 6 of Fig. 3, and

Fig. 7 is a vertical section through a portion of a receptacle and cap illustrating a 105 modified method of employing our invention, the string or cord in this instance not being directly carried by the cap but sepa-

rately extended over one edge of the receptacle prior to the application of the cap thereto.

In the drawings, referring to Figs. 1 to 6 inclusive, 10 indicates a known form of receptacle, in this instance, a tumbler, for illustration, 11 the contents thereof, and 12 the cap or closure for said receptacle, said cap or closure being of thin flexible material, preferably of pyroxylin nature, and comprising a top 13 and depending annular skirt portion 14, which is intended to closely cling against the sides of the receptacle 10. In the construction presented in Figs. 1 to 6 inclusive, we equip the cap or closure with a string or cord 15 and connect the same with the cap or closure by perforating the lower portion of the skirt 14 and extending the string therethrough, a part of the string 20 being exposed at the outer side of the cap or closure and a sufficient portion thereof being within the cap or closure to extend across one side of the upper edge of the receptacle 10 upon the application of the cap or closure to said receptacle, as shown in Fig. 2. The string or cord 15 by closely fitting the perforation in the skirt of the cap, will retain its position so that the article to be handled and sold will be self-contained, the 30 cap then carrying and holding the string or cord ready for use when the cap or closure is applied to a receptacle. The cap or closure is, as aforesaid, of flexible material, and when applied to the receptacle 10 a portion 35 of the string or cord 15 extends from the perforation 16 in the skirt 14 up along the side of the receptacle and over the upper edge of the same; that portion of the string or cord at the inner side of the cap 40 serves, when the cap is placed on a receptacle, to force the adjacent side portions of the skirt 14 outwardly, as at 17 (Fig. 5), and also prevents the top of the cap from fully seating on the upper edge of the receptacle, thereby leaving along the string or cord a vent or air channel out through 45 which the contained air may escape from within the cap during the application of the same to the receptacle, instead of the air being trapped within the cap. The air within the cap is forcibly discharged around the string or cord 15 while the cap is being pressed downwardly upon the receptacle and finally when the cap has become firmly 50 seated, the string or cord 15 will be pulled outwardly from the cap and receptacle, after which, preferably, the cap will be given a final downward pressure so that that portion of its top which was held upwardly 55 by the thickness of the string or cord crossing the edge of the receptacle, may pass into firm engagement with the receptacle.

In Fig. 7 the tumbler or receptacle is numbered 20, its contents 21, and its cap 22, 60 said cap comprising, the same as the cap

shown in Fig. 1, a top portion 23 and an annular depending skirt portion 24 to closely fit upon the sides of the receptacle 20. In Fig. 7 we illustrate the string or cord, numbered 25 therein, as extending from within the receptacle over the upper edge thereof and down between the skirt or flange 24 and the side of the receptacle, and said string or cord 25 is used for the same purpose and performs the same duty as the string or cord 15 shown in Figs. 1, 2, 4 and 5 inclusive. In the construction shown in Figs. 1 and 2 the string or cord 15 is carried by the cap 12 as a part of a complete commercial apparatus, whereas in the construction shown in Fig. 7 the string or cord 25 is not carried by the cap but is placed by the user of the receptacle and cap across the upper edge of the receptacle prior to the application of the cap thereto, and upon the cap having been applied to the receptacle the string or cord 25 is drawn out from between the cap and receptacle in the same manner that the string or cord 15 is withdrawn from the receptacle shown in Figs. 1 and 2. The string or cord 25 creates a vent for the air which would otherwise be entrapped within the cap 22. We prefer the construction shown in Figs. 1 and 2 since with such construction the string or cord 15 is carried by the cap and therefore always present for immediate use, whereas with the employment of the invention in the manner indicated in Fig. 7, the string or cord 25 is separate from the cap and liable to become misplaced.

Our invention involves apparatus, to-wit, the cap having a thin flexible resilient depending skirt portion, string or cord and receptacle, and also a new method for preventing air from becoming trapped within the caps of the character involved herein when the same are applied to receptacles with which they pass into close engagement. The invention remedies an objection which has long existed, in connection with the application of light-weight flexible caps to jars and the like.

We employ the word "string" or "cord" in the foregoing specification in a generic sense, and said string or cord may be of any suitable character and of any suitable material and diameter, the only essential features being that it shall be sufficiently flexible to snugly fold over the edge of the receptacle and extend down between the skirt of the cap and the side of the receptacle and that it be capable of being withdrawn from the receptacle without destroying the cap.

The cap or closure is preferably of the slip-cover type and preferably formed from thin sheet pyroxylin material or equivalent substance.

Our invention also possesses the advantage of permitting the formation of a par-

tial vacuum within the receptacle sufficient to quite firmly hold the cap in place, and in this use of the invention the cap and string will be applied to the receptacle, and by 5 means of the thumb or hand the middle portion of the cap will be depressed or dished inwardly to discharge through the vent a part of the air that may be still within the top of the receptacle, after which the string 10 or cord will be withdrawn to permit the sealing of the vent.

What we claim as our invention and desire to secure by Letters Patent, is:

1. A receptacle having plain exterior surfaces about its mouth, a cap of flexible material closely applied thereto and having a top to engage the lip of the receptacle and a depending skirt portion to pass downwardly over the sides of the receptacle and which is 20 also flexible and resilient, and has a transverse hole in it, and a flexible string threaded through said hole so as to become detachably connected with and carried by the cap and which string on the application of 25 the cap becomes interposed between the lip and side of the receptacle and said cap and adapted at the location of the string to prevent the top of the cap from sealing on said lip and to flex said skirt outwardly, thereby 30 creating a temporary vent, said string to be

finally withdrawn and said skirt on the withdrawal of said string being adapted to automatically regain its initial condition, for completing the sealing of the receptacle.

2. The method hereinbefore described of 35 avoiding the entrapment of air at the top of a substantially filled receptacle by the application of a closure to said receptacle, which consists in providing a close fitting flexible slip-cap, interposing a string between the lip and side of the receptacle and said cap when the cap is being applied to position, compressing the cap downwardly upon said receptacle and string, and thereafter dishing the top of said cap downwardly and withdrawing said string so as to permit the skirt portion of the cap to regain its initial shape and cling to the receptacle and also so as to positively effect the discharge of the air entrapped in the top of 40 45 the receptacle and assure the sealing of the cap on the receptacle.

Signed at New York city, in the county of New York and State of New York, this 13th day of November A. D. 1916.

ALFRED INGRAM.
HARRY INGRAM.
